UNITED STATES PATENT OFFICE.

JOSEPH KRUPKA, OF COALRIDGE, OHIO.

EXPLOSIVE SHELL.

1,237,658.

Specification of Letters Patent. Patented Aug. 21, 1917.

Application filed May 28, 1917. Serial No. 171,436.

To all whom it may concern:

Be it known that I, JOSEPH KRUPKA, subject of the Emperor of Austria, residing at Coalridge, in the county of Noble and State 5 of Ohio, have invented certain new and useful Improvements in Explosive Shells, of which the following is a specification.

This invention relates to certain new and useful improvements in explosive shells.

10 The primary object of the invention is the provision of an explosive shell that is easy and inexpensive to manufacture and is adapted to explode upon violently striking any object during the forward movement 15 thereof.

20 A further object of the device is to provide an explosive shell having an internal exploding mechanism arranged with a firing means retained inoperative during the handling and shipment thereof but adapted for 25 operative positioning when fired from a gun or projector.

With these general objects in view and others that will appear as the nature of the 25 invention is better understood, the same consists in the novel construction, combination and arrangement of parts hereinafter fully described, illustrated in the accompanying drawing and pointed out in the appended 30 claims.

In the drawing forming a part of this application and in which like numerals refer to corresponding parts throughout the several views;

35 Figure 1 is a central longitudinal sectional view through the device with the parts thereof inoperatively positioned.

Fig. 2 is a similar view with the mechanism operatively arranged but with the explosive removed.

Fig. 3 is a view similar to Fig. 1 with the mechanism illustrated in its exploding position.

Fig. 4 is a transverse sectional view taken 45 upon line IV—IV of Fig. 1.

Fig. 5 is a transverse sectional view taken upon line V—V of Fig. 3, and,

Fig. 6 is a forward portion of a modified 50 form of torpedo shown in central longitudinal section.

The present invention broadly consists in a shell 10 adapted to receive an explosive such as dynamite 11 and having a bullet or point 12 arranged in the forward open end 55 of the shell while suitable mechanism is provided for exploding the dynamite 11 when

the bullet 12 strikes an object. A tubular casing or well 13 is centrally held within the shell 10 surrounded by the dynamite 11 by means of oppositely projecting arms 14 60 attached to lugs 15 upon the inner wall of the shell, an opening 16 being provided in the bottom of the well 13 adapted to receive a suitable percussion cap or fulminate.

A piston 18 is slidably arranged within 65 the well 13 having an inner head 19 in the form of a disk slidably fitted within the well and provided with a centrally projecting point or firing pin 20 adapted for exploding the cap 17 when the piston is moved inwardly through the opening 16. The outer head 21 of the piston is also in the form of a disk and has a centrally projecting rod 22 carried thereby slidably arranged centrally through the bullet 12 within an axial 70 bore 23 provided in the bullet.

A lever 24 is hinged as at 25 within the shell 10 adapted to bear upon the portion 26 of the piston 18 and having an operating bar 26 slidably carried through a side strap 80 28 upon the well 13 and within an opening 28 in the base 29 of the shell.

When the shell is arranged for transportation, the rod 22 is positioned slightly inwardly of the outer end of the bore 23 85 with the piston head 21 lying flush within the well 13 while the lever 24 will be substantially parallel with the arms 14 and the lower end of the bar 27 will be slightly inwardly of the outer face of the base 29. 90 This arrangement of the rod 22 will permit the positioning of the suitable sealing or retaining means such as wax 30 in the outer end of the bore 23 and a similar quantity of wax 31 within the outer end of the opening 28 as best illustrated in Fig. 1 of the drawing. The torpedo is adapted to be fired or projected by a suitable member such as a cannon or gun and in preparing the torpedo for firing, the bar 27 is forced inwardly 95 which projects the rod 22 slightly outwardly of the bore 23 as illustrated in Fig. 2 and whereupon when the free end of the rod 22 and the bullet 12 strike an object, the rod 22 will be forced inwardly 100 for mounting the piston 18 in a corresponding direction, thereby forcing the pin 20 through the cap 17 and exploding the same for igniting the explosive 11 which is adapted to disrupt the shell 10, separate the bullet 12 therefrom and project any such articles as scrap iron 32 which is positioned

105 110

within the shell 10 in all directions. A serviceable torpedo for times of war is arranged which may be made of any desired size, it being understood that the bar 27 5 may be moved inwardly for projecting the rod 22 in any desired manner such as by means of a pin (not shown), arranged in the gun by means of which the torpedo is projected. It will be understood that the 10 explosive 11 is arranged to permit of slight movement in the rod 22, lever 24 and bar 27 without discharging the device.

In the modified form of the device shown in Fig. 6 the shell 10' is arranged with a bullet 12' having a rod 22' centrally and 15 slidably arranged therethrough, and provided with a head 21' with a well 13'. Dynamite 11' is provided in the shell 10' while a percussion cap 17' is arranged adjacent 20 the bottom of the well 13' for engagement by the head 21' when the bullet of said rod comes in contact with the object during the forward movement of the torpedo. The 25 exploding of the cap 17' is adapted to burst the well 13' for igniting and discharging the dynamite 11'.

What I claim as new is:—

1. A device of the class described comprising a shell adapted for holding an explosive, a bullet in one end of the shell arranged with an axial bore, a well mounted within the shell, a percussion cap carried by said well, an exploding member for said cap shiftably arranged within the well, an operating rod for the said exploding means 30 slidably arranged within the said bore and sealing means in the outer end of the said bullet bore and overlying the said rod.

2. A device of the class described comprising a shell adapted for holding an explosive, a bullet in one end of the shell arranged with an axial bore, a well mounted within the shell, a percussion cap carried by said well, an exploding member for said cap shiftably arranged within the well, an operating rod for the said exploding means 35 slidably arranged within the said bore, an operating lever for said exploding means pivoted within the shell and a positioning bar for said lever longitudinally shiftably 40 positioned within the shell and slidably arranged through the rear end thereof.

3. A device of the class described comprising a shell having a base provided with an opening therethrough, a bullet in the end 45 of the shell opposite the said base and provided with an axial bore, a tubular casing axially positioned within the shell attached to the opposite sides thereof having a cap receiving opening in its inner end, a 50 percussion cap within said opening, an explosive arranged within the shell substantially surrounding the said casing, a double headed piston slidably arranged within the casing, a firing rod carried by 55 said piston slidably arranged through said bore, a firing pin carried by the inner end of the said piston having an inward path of movement in the plane of said cap, a movement imparting lever for said piston pivoted within the said casing and an operating 60 bar for said lever slidably arranged within the shell and within the opening of the 65 shell base.

In testimony whereof I affix my signature.
JOSEPH KRUPKA.
